UNITED STATES PATENT OFFICE

WILLIAM K. RANKIN, OF SCOTIA, NEW YORK, ASSIGNOR TO GENERAL ELECTRIC COMPANY, A CORPORATION OF NEW YORK

SWITCH OPERATING AND CONTROLLING MECHANISM

Application filed October 15, 1925. Serial No. 62,842.

My invention relates to electric switches and particularly to the operating and controlling mechanism for switches of relatively large proportions which are adapted to control high potential, large capacity circuits. 5 One object of my invention is the provision of an improved trip-free switch operating mechanism, one feature of the mechanism being that the reaction of the switch on the mechanism supplies the force by which the latching mechanism is moved to release position. 10

Another object is the provision of an improved trip-free switch operating mechanism in which the relatively sensitive latching means which controls the tripping of the mechanism is mounted in such a manner that it is substantially free from jars incident to the operation of the operating mechanism. 15

My invention will be better understood from the following description taken in connection with the accompanying drawings, and its scope will be pointed out in the appended claims. 20

Referring to the drawings, Figs. 1 and 2 are side elevations partly in section of a switch operating mechanism involving my invention, Fig. 1 showing the mechanism in closed circuit position, and Fig. 2 showing it 25 in open circuit position.

As this mechanism is particularly adapted for the operation and control of switches of relatively large capacity and hence of massive construction I have shown the mechanism as solenoid operated. However, other power actuating means may be employed if desired and in case of an emergency, a hand operated means also may be used. The base-plate or supporting frame 1 supports the sole- 30 noid core structure 2 and forms a part of the magnetic circuit thereof. Within the core is the winding 3 and the plunger 4 from the top of which the rod 5 having the nut 6 ex- 35 tends up through the core. Two similar lugs 40 8 depend from the base 1 by which the va-

rious levers and links forming the mechanism are supported. The shoulders 9 on the lugs 8 form the bottom stop for the plunger and the central portion 10 of the core on which is a non-magnetic disk 11 forms the upper stop for the plunger. 50

The main switch lever or switch operating member 12 extends between and is pivoted to the lugs 8 at 13. Pivoted to and extending upwardly from the left hand end of the main lever 12 is the rod 14 through which operative connection is made with the switch (not shown). The switch may, for example, be similar to that shown in the patent to Hentschel No. 957,835, May 10, 1910, in which the rod 11 corresponds with the rod 14 of the present case. Bell crank lever 15 pivoted at 16 to the lugs 8 has double downwardly extending arms 17 to which is pivoted the floating lever 18. This lever is double and between the two halves at one end is the roller 19 which engages the upper face 20 of lever 12. To the opposite end of floating lever 18 is pivoted link 21 which pivotally connects with the plunger 4. Toggle links 23 and 24 forming a restraining device or toggle connect the same end of the floating lever 18 with laterally projecting ears 25 on the lugs 8. Links 24 are provided with stop pins 26 which engage the lugs 8 when the mechanism reaches the closed circuit position shown by Fig. 1. In this position it will be noted that the toggle is slightly over-set. It is of course understood that the links 21, 23 and 24 are each double, being duplicated on each side of the main lever 12. The bell crank 15 has a single arm extending to the right to which is pivoted a retaining means of relatively light construction comprising the underset toggle links 28 and 29. To the common point 30 of these links is attached the latching device comprising the toggle links 31 and 32, also light and sensitive, which in the over-set position engage the stop 33. 75

The toggle links 31, 32 comprising the 90

latching device are mounted on the support 34, shown as a part of the frame 1. By thus mounting the latching device separately and independently of the switch operating mechanism the parts thereof are not moved when the mechanism operates to close the switch and hence are not liable to be thrown to release position by jars incident to the closing movement of the mechanism.

10 An electroresponsive device comprising the solenoid 35 and the plunger 36 is adapted to cause the release of the aforesaid latching device upon the occurrence of a predetermined circuit condition, as for example an over-load. Trip lever 37 engaging the plunger 36 is provided for manual tripping of the mechanism. For the operation of the mechanism by hand to close the switch, which may become necessary in an emergency, any 20 suitable device may be applied to the rod 5 beneath the nut 6 by which the necessary force can be exerted on the rod.

In the closed circuit position of the apparatus, as illustrated in Fig. 1, the reactive force of the switch is transmitted through the main operating lever 12, roller 19, floating lever 18 to the toggle links 23 and 24. These links also sustain the weight of the plunger. The upper face 20 of lever 12 has an inclination such that the roller 19 tends to roll or be cammed off the end of the lever 12 and move the toggle links 23 and 24 from the present over-set position to an under-set position. Movement of the roller 19 and floating lever 18 to the right however is prevented by the bell crank 15 and the electroresponsive toggle mechanism connected therewith. Upon the actuation of the plunger 36, toggle links 31 and 32 are pushed 40 over center releasing toggle links 28 and 29 and permitting bell crank 15 to rock in a counterclockwise direction. Roller 19 thereupon is cammed off and rolls over the end of lever 12 releasing it and the switch connected therewith. Floating lever 18 has thereby been moved a sufficient distance to the right to cause the toggle links 23 and 24 to release the plunger 4 whereupon it drops against the stop 9 and rocks the floating lever 18 counterclockwise. The roller 19 is thus returned 50 over the end of the main lever and by reason of the weight of the bell crank and the links 28 and 29 is restored to the position shown in Fig. 2. By this same movement toggle links 28 and 29 and toggle links 31 and 32 are also restored.

When the switch is to be reclosed the solenoid is energized and upward movement of the plunger 4 is transmitted through links 21, 60 floating lever 18, roller 19, and main operating lever 12 to the rod 14. The inclination of the face 20 engaged by roller 19 is such that the floating lever tends to move to the right but is restrained therefrom by the bell 65 crank and the toggle mechanism connected

therewith. Should there occur during the closing operation an overload or short circuit for example for which the device 35, 36 is set to respond, the floating lever 18 is immediately released, the roller 19 rolling over the end of the main lever 12 as already described. The mechanism thus is tripped free.

An important feature of my invention is the provision of means whereby the reactive force of the switch supplies the force by which the holding latch is moved to release position. A large and heavy switch requires not only a considerable force to close it but a force scarcely less to hold it closed. The restraining means which in the present instance 75 comprise the links 23 and 24 must therefore be relatively large and heavy. By the mechanism above described a fraction of the reactive force of the switch is made use of to move the restraining means to release position while a comparatively light and sensitive latching device is used to control the restraining means. In the arrangement disclosed the restraining means also opposes the weight of the solenoid plunger thus further 80 relieving the light and sensitive control latch.

While I have described only one embodiment of my invention, I do not wish to be limited to the particular form shown and described as it will be apparent that many modifications therein may be made without departing from the scope of my invention as set forth in the appended claims.

What I claim as new and desire to secure 100 by Letters Patent of the United States, is:

1. Switch operating and controlling mechanism comprising a switch operating member, a restraining device for holding the member in operated position, said restraining 105 device being disengageably related to said switch operating member, a latching device for controlling said restraining device, and means operated by the reaction of the switch on the operating member for moving said 110 restraining device from a restraining to a releasing position in response to actuation of said latching device.

2. Switch operating and controlling mechanism comprising a switch operating member, a restraining device for holding the member in operated position, said restraining 115 device being disengageably related to said switch operating member, latching means for said restraining device, and means coacting 120 with said restraining device whereby the reactive force of the switch on the operating member tends to move said device from a holding position to releasing position in response to actuation of said latching means.

3. Switch operating and controlling mechanism comprising a lever, means for operating the lever, a restraining device for holding the lever in operated position, said device being released by longitudinal movement of 130

the lever, means whereby the reaction of the switch on the lever tends to move it longitudinally, and an electroresponsive device for controlling the longitudinal movement of the lever.

4. Switch operating and controlling mechanism comprising a switch operating member, a floating lever operatively connected therewith, the connection tending to cause longitudinal movement of the lever, means for operating the lever, a restraining device for the lever arranged to be released by longitudinal movement of the lever, and an electroresponsive device for controlling said movement of the lever.

5. Switch operating and controlling mechanism comprising a switch operating member having an inclined face, a floating lever arranged to engage said inclined face, a solenoid operatively connected with the floating lever, a toggle device adapted to hold the floating lever in operated position when offset and to buckle when the floating lever moves longitudinally, a movable support for the floating lever and an electroresponsive device connected with the movable support.

6. In combination, a supporting frame, having mounted thereon a switch operating mechanism, a restraining device disengagably related to said operating mechanism, and a relatively sensitive latching device operatively related to said restraining device and arranged to initially control the release of the switch operating mechanism, said latching device being separately carried by said supporting frame whereby it is substantially freed from jars incident to the operation of the switch operating mechanism.

7. Switch operating and controlling mechanism comprising an operating member, a restraining device for holding the member in operated position, latching means for controlling the restraining position of said device, and means for transmitting the reactive force of the switch from the operating member to said restraining device to cause it to move to its releasing position in response to actuation of said latching means.

8. Switch operating and controlling mechanism comprising an operating member, toggle mechanism for restraining the member in operated position, and a member disengageably related to said operating member responsive to electromagnetic means for controlling the restraining position of said toggle mechanism, said members adapted to transmit the reactive force of the switch in response to actuation of said electromagnetic means from the operating member to said toggle mechanism to cause it to collapse and to thereby effect release of said operating member.

9. Switch operating and controlling mechanism comprising an operating member, toggle mechanism for restraining the member in

operated position, a floating lever operatively connected to said toggle mechanism, and a latching device coacting with said floating lever to cause initial collapsing movement of the toggle mechanism, said operating member thereupon adapted to transmit the reactive force of the switch to the floating lever to cause final collapse of the toggle mechanism and consequent release of said operating member.

10. Switch operating and controlling mechanism comprising an operating member, toggle mechanism for restraining the member in operated position, a lever having an operative connection with said toggle mechanism and a camming connection with said operating member, and electroresponsive means adapted to control the initial movement of said lever for causing movement of the toggle mechanism towards releasing position, said operating member thereupon transmitting the reactive force of the switch to the toggle mechanism through said camming connection to complete the aforesaid releasing movement.

11. Switch operating and controlling mechanism comprising an operating member, toggle mechanism for restraining the member in operated position, a floatingly mounted member operatively connected to said toggle mechanism and having a camming connection with said operating member, and electroresponsive means adapted to cause bodily movement of the floating member for effecting initial releasing movement of said toggle mechanism, said operating member adapted to transmit the reactive force of said switch through said camming connection to said toggle mechanism to complete said releasing movement.

12. Switch operating and controlling mechanism comprising an operating member, power actuating means, a floating member operatively connected to said power actuating means and disengageably connected to said operating member for effecting closing movement thereof, toggle mechanism connected to said floating member for restraining said operating member in its closed position, and electroresponsive means adapted to effect bodily movement of said floating member for causing initial releasing movement of said toggle mechanism, completion of said releasing movement being effected by the reactive force of the switch acting through said operating arm and floating member.

13. Switch operating and controlling mechanism comprising an operating member, solenoid actuating means for effecting switch closing movement of said member, a lever operatively related to said solenoid actuating means and operating member for transmitting switch closing movement to said member, said lever having a floating pivot

adapted to be restrained in a fixed position, toggle mechanism connected to said lever for restraining the lever in operated position, and a latching device for controlling the position of the floating pivot of said lever, said operating member being adapted to transmit switch reactive force to said lever to cause movement of said floating pivot and collapse of said toggle to releasing position in response to actuation of said latching device.

In witness whereof, I have hereunto set my hand this 14th day of October, 1925.

WILLIAM K. RANKIN.
